US00D606405S

(12) **United States Design Patent**
Takata et al.

(10) **Patent No.:** **US D606,405 S**
(45) **Date of Patent:** **** Dec. 22, 2009**

(54) **CONTAINER**

(75) Inventors: **Carolyn Takata**, Laguna Niguel, CA (US); **Thomas Murphy**, Lake Mills, WI (US); **Todd L. Peseck**, Shawnee, KS (US)

(73) Assignee: **Silgan Containers LLC**, Woodland Hills, CA (US)

(**) Term: **14 Years**

(21) Appl. No.: **29/318,026**

(22) Filed: **May 12, 2008**

(51) **LOC (9) Cl.** **09-01**

(52) **U.S. Cl.** **D9/500; D9/428**

(58) **Field of Classification Search** **D9/500, D9/502, 516, 549, 556-558, 414, 424-426, D9/428-429; D7/601-602, 629-630; 215/379, 215/381-383; 220/574, 657, 660, 669-673, 220/675**

See application file for complete search history.

(57) **CLAIM**

We claim the ornamental design for a container, as shown and described.

DESCRIPTION

FIG. 1 is a top, perspective view of a container showing our new design;

FIG. 2 is a bottom perspective view thereof;

FIG. 3 is a front elevation view thereof, the left side, right side and rear elevation views being identical;

FIG. 4 is a top plan view thereof; and,

FIG. 5 is a bottom plan view thereof.

The ornamental design which is claimed is shown in solid lines in the drawings. The broken lines in the drawings are for illustrative purposes only and form no part of the claimed design.

1 Claim, 5 Drawing Sheets
